DESIGN FOR A DRESS

Samuel Zahn, New York, N. Y.

Application November 30, 1937, Serial No. 73,267

Term of patent 3½ years

To all whom it may concern:

Be it known that I, Samuel Zahn, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The floral elements on the front waist and sleeve portions are comprised of superimposed shirred material with attached stitched-down stems, said stems being caught by a band in the manner shown and hang loosely on the blouse section, below said band.

I claim:

The ornamental design for a dress, substantially as shown, and described.

SAMUEL ZAHN.
